(Model.)

A. E. FRENCH.

Fastener for the Meeting Rails of Sashes.

No. 228,523.

Patented June 8, 1880.

Washington, D. C.

UNITED STATES PATENT OFFICE.

ALBERT E. FRENCH, OF DETROIT, MICHIGAN.

FASTENER FOR THE MEETING-RAILS OF SASHES.

SPECIFICATION forming part of Letters Patent No. 228,523, dated June 8, 1880.

Application filed April 16, 1880. (Model.)

To all whom it may concern:

Be it known that I, ALBERT E. FRENCH, a citizen of the United States, residing at Detroit, in the county of Wayne and State of Michigan, have invented certain new and useful Improvements in Fasteners for Meeting-Rails of Sashes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an improvement in the class of sash-locks for the meeting-rails of window-sash; and it consists in two plates pivoted together at their center, one of which is stationary, the other made to turn on the 20 central pivot, each provided with an annular flange on its inner face, made to fit one within the other, whereby an inclosed chamber is formed between the plates for the reception of suitable locking mechanism, and the movable plate having rigidly fixed to its outer face a 25 bar or bolt whose motion is governed by the plate to which it is joined; also, in certain other details of construction, hereinafter more fully described and shown.

30 In the drawings, Figure 1 is a perspective view of my invention. Fig. 2 is a plan view of same. Fig. 3 is a side elevation, showing the bar in position. Fig. 4 is an end view. Fig. 5 is a horizontal section through the line 35 xx of Fig. 4, showing the interior construction. Fig. 6 is a vertical section through the line yy of Fig. 5, showing the central post or pivot.

30 A is the main plate, which is provided with suitable screw-holes for attaching it to the sash, and having the annular flange B and central post, a.

40 C is a flat bolt resting upon the plate within the flange, an elongated opening being provided in its center, through which projects the post a, and which permits the bolt to move freely back and forth. Its movement is regulated and limited, and it is kept in place by small projections or posts F, inserted in the 45 plate at its side and end, and a flat spring, D, occupying the outer circumference of its cen-

tral opening around post a. Its smaller end projects through a recess in flange B.

o is a recess in the side of the bolt for the accommodation of the blade or bit of a key 55 by which the bolt is actuated.

E is the upper or outer disk, which is united to, or cast solid with, the bar e, and is also provided on its inner face with a flange or rim of sufficient diameter to inclose flange B 60 of plate A when placed in position over it. A recess is provided in this flange, into which fits the end of bolt C when shot forward, as shown in Fig. 5.

G is a projecting pin on the side of bar e, to 65 prevent said bar being turned from the outside by the insertion of any instrument between the sash.

70 My device is operated as follows: It is firmly attached to the top rail of the lower sash of a window by screws through plate A. The disk E is then turned so that the projecting end of bar e is beneath hook K on the bottom rail of the upper sash. It is then locked in position by inserting the key through the key-hole p, 75 when the bit or blade of the key occupies the recess o in the side of bolt C. The key is then turned forward, causing the bolt C to slide forward, so that its end passes through the slot in flange B into recess H of the outer flange, 80 thus holding disk E firmly in place, so that it cannot turn on pivot a until released by reversing the movement with the key. The projection G on the side of bar e is designed to prevent the bar from being turned from the 85 outside when not locked by inserting the blade of a knife or other similar instrument between the sash and bearing against it.

80 It is obvious that any instrument inserted between the sash and interposed between the hook K and projection G would be tightly clamped between the two by any lateral pressure upon bar e, and the resistance would increase in proportion to the pressure exerted.

90 In order to prevent my lock being taken apart, the top of post a may be riveted, instead of uniting the parts by a nut or screw-head, as shown in the drawings.

Having thus described my invention, what I claim, and desire to secure by Letters Patent, is—

1. In a sash-lock, the fixed flanged plate A,

having central post, *a*, and sliding bolt *C*, arranged within the flange, to be operated by a key, in combination with the pivoted disk *E*, provided with the horizontal bar *e*, rigidly fixed thereto, substantially as described, and for the purpose set forth.

2. The plate *A*, having the recessed flange *B*, central post, *a*, and studs *F*, the sliding bolt *C*, arranged within the flange and between the guide-studs, to be actuated by a key, in combination with the recessed flanged disk *E*, pivoted to the central post, and provided with the bar *e*, rigidly attached thereto, substantially as and for the purpose set forth.

3. The plate *A*, having the recessed flange *B*, central post, *a*, and studs *F*, the sliding bolt *C*, arranged within the flange, and provided with spring *D* in its opening around post *a*, in combination with the pivoted disk *E*, having bar *e* rigidly fixed thereto, and the recessed flange, substantially as described, and for the purpose specified.

In testimony whereof I affix my signature in presence of two witnesses.

ALBERT E. FRENCH.
